US00D891771S

(12) **United States Design Patent** (10) **Patent No.:** **US D891,771 S**
Lee et al. (45) **Date of Patent:** **** Aug. 4, 2020**

(54) **PROTECTIVE HANG COVER SKIN FOR ELECTRONIC DEVICE**

(71) Applicant: **elago CO. LTD**, Goyang-si, Gyeonggi-do (KR)

(72) Inventors: **Chan Woo Lee**, Goyang-si (KR); **Chong Min Kim**, Seoul (KR)

(73) Assignee: **elago CO. LTD**, Goyang-si, Gyeonggi-Do (KR)

(**) Term: **15 Years**

(21) Appl. No.: **29/686,091**

(22) Filed: **Apr. 2, 2019**

(51) LOC (12) Cl. **03-01**

(52) U.S. Cl.

USPC **D3/269**; D3/215; D3/302

(57) **CLAIM**

The ornamental design for a protective hang cover skin for electronic device, as shown and described.

DESCRIPTION

FIG. 1 is a front, top and right perspective view of protective hang cover skin for electronic device showing claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, bottom and right perspective view thereof;

FIG. 9 is a cross-sectional view taken along line 9-9 shown in FIG. 2; and,

FIG. 10 is a front, top and right perspective view thereof with a top portion open in use.

The broken lines shown in FIG. 10 depict environment and form no part of the claimed design.

1 Claim, 9 Drawing Sheets
